**KITE WITH FLEXIBLE BALLOONING
SAIL SURFACES**

Carl Edward Johnson, 322 Hill St., Rte. 1, Box 355A,
Coloma, Mich. 49038
Filed Dec. 27, 1966, Ser. No. 604,794
10 Claims. (Cl. 244—153)

ABSTRACT OF THE DISCLOSURE

The kite disclosed has a T-shaped frame with a cross bar at the front that is approximately twice as long as the longitudinal member connected rigidly and at right angles to the center of the front cross bar. The supporting surface is a sheet or film of flexible material having its front edge secured along the cross bar and its longitudinal center connected along the rearwardly extending longitudinal base of the T-shaped frame. The sail is slack along its side edges so as to balloon up in flight in symmetrically curved surfaces rearwardly of the front cross member and laterally of the longitudinal axis of the kite. A tail surface of self sustaining rigidity is secured in upwardly and rearwardly inclined position on the rear end of the longitudinal frame member.

Summary of invention

The inventive ingenuity in the kite lies in the relationship between its parts, as outlined in the abstract of disclosure, which provides a kite having extremely stable, high flying characteristics, combined with light weight and economy of production. The kite provides a high lift to drag ratio that adjusts automatically to different wind conditions and permits the kite to be flown in light winds and air currents, and also permits the kite to glide down when the wind decreases.

The drawings of which there is one sheet illustrate a preferred embodiment of the kite.

FIGURE 1 is a top plan view of the kite in horizontal flight.

FIGURE 2 is a front elevational view of the kite in flight.

FIGURE 3 is a side elevational view of the kite in horizontal flight.

FIGURE 4 is a fragmentary cross sectional view taken along the plane of the line 4—4 in FIGURE 1.

FIGURE 5 is a fragmentary cross sectional view taken along the plane of the line 5—5 in FIGURE 1.

The kite consists of a T-shaped frame formed of a rigid transverse front member 1 connected at right angles to a rearwardly extending longitudinal bar or frame member 2 with the longitudinal member connected to the center of the transverse member and being approximately one-half the length of the transverse member. In practice the frame members 1 and 2 are sticks of light wood and may be secured together as by adhesive indicated 3 in FIGURE 5. Secured along the undersides of the frame members 1 and 2 are sail members 4 and 5 formed of films or sheets of flexible material such as light cloth, paper or plastic. The sail members have leading edges 6 that are secured to the transverse member and longitudinal edges 7 that are secured continuously along the longitudinal member and outer side edges 8 that are substantially longer than the diagonal distance between the ends of the transverse member 1 and the rear point of connection of the sail members to the longitudinal member. This shape of the sail members is achieved by cutting or forming the sail members in a plane surface as shown by the dotted line in FIGURE 1 in which the leading edges 6A extend forwardly at an obtuse angle to the longitudinal

2

inner edges of the sail members thus leaving slack in the outer side edges 8 when the sail members are secured to the frame members. The particular reversely curved contour of the outer side edges 8 having convex curves 9 and 10 at their ends joined by a concave curve 11 are optional but provide a desirable birdlike appearance of the kite in flight. When the kite is in flight the slack in the sail members causes them to balloon upwardly in upwardly convex curved surfaces 12 that converge downwardly along the sides of the longitudinal member 2 and downwardly and forwardly to the front cross member 1.

Secured to the rear end of the longitudinal member 2 is a tail 13 of light but shape retaining material such as the sheet of styrofoam material indicated in FIGURE 4. The tail 13 is conveniently removably mounted in place by providing a hole 14 through the tail through which the rear end of the longitudinal member 2 projects. A looped rubber band 15 has its forward end secured to the underside of the longitudinal member as by the staple 16 and passes downwardly through a slit or notch 17 formed in the lower edge of the tail and then upwardly in a loop 18 over the rear end of the longitudinal member to draw the lower end of the tail forwardly against the edges of the hole 14 and against a positioning block 19 secured to the underside of the longitudinal member. The tail is thus positioned in an upward and rearward inclined position relative to the frame of the kite and projects above and below the frame with the larger portion of the area of the tail being exposed between the upwardly ballooned surfaces 12 of the sail members 4 and 5.

A connection indicated generally at 20 is provided on the underside of the longitudinal member for connecting a flying string 21 to the kite. For most stable operation of the kite, the connection 20 consists of a yoke of flexible material such as string having relatively short forward arm 22 and a relatively long rear arm 23. The rear arm 23 may include a longitudinally yieldable section such as a rubber band 24 secured in place by a staple 25. The front arm 22 is also conveniently attached to the underside of the transverse member by a staple 26 (see FIGURES 5 and 6). The flying string 21 may be connected to the yoke by a swivel conventionally illustrated at 27.

Desirably the leading edges 6 of the sail members are detachably secured along the underside of the transverse member 1 by means of a strip of adhesive material 28 which overlaps the edge of the sail and the adjacent surface of the transverse member. This permits adjustment of the slack in the sail members to equalize the slack in each sail and provide lateral stability to the kite. It is further convenient to make both sail members 4 and 5 from a single sheet of material and to attach the longitudinal center of the combined sail members to the longitudinal frame member 2 by providing a series of holes 29 in the sail member. A second strip of adhesive material 30 is then placed along the underside of the longitudinal member, passing through the holes 29 to adhere to the longitudinal member at spaced points and hold the sail member or members in position.

The kite constructed as described above is capable of numerous variations in proportion, shape and weight and these variations will vary the flight characteristics of the kite. Desirably the center of gravity of the kite is positioned generally under the maximum ballooned portion of the sail members as at 31 in FIGS. 1 and 3 and the weight of the tail 13 is one-twelfth of the total weight of the kite. Within this general portion the weight of the tail may be relatively concentrated by making it of smaller area and greater thickness and this variation is desirable for flying the kite in high wind velocity. A broader thinner tail is more desirable under light wind conditions. Regardless of the relative size of the tail the upwardly and rearwardly projecting position of the tail as shown in full lines

in FIGURE 3 permits the tail to be acted upon by rearward air flow between the sails to prevent the kite from nosing forward and diving. The full line position in FIGURE 3 thus illustrates one extreme position of flight of the kite while the dotted line position 13A illustrates another extreme position in which the kite will exert maximum lift by reason of the wind acting on the ballooned sails and creating minimum drag on the tail in its horizontal position.

Due to the minimum structure and light weight of the kite for any given size or area of the sail members and the stabilizing effect of the tail, the kite can be flown to relatively high altitudes and lift a maximum amount of string 21 with which the kite is flown. The balancing effect of the tail 13 permits the kite to glide forwardly and downwardly without nosing over or stalling should the supporting air currents decrease in velocity.

What is claimed as new is:

1. A kite comprising a rigid central longitudinal member,
a rigid transverse member connected in crossing relation to said longitudinal member adjacent to the front end of the latter and centrally of the transverse member,
sail members of flexible flat sheet material having central edges connected to said longitudinal member in flat coextensive relation from said transverse member to a point adjacent the rear end of the longitudinal member,
said sail members having leading edges that extend in forward obtuse angles from said central edges when the sail members are arranged in a plane and which are connected in straight continuous relation along said transverse member to adjacent the ends of the latter,
side edges on said sail members of greater length than the straight line distance between the outer ends of said leading edges and the rear ends of said central edges and extending loosely therebetween,
a flat tail member of self sustaining rigidity connected to said longitudinal member behind said sail members and disposed at an upwardly and rearwardly inclined angle to the plane of said longitudinal and said transverse members,
and a connection for a string arranged to apply a downward force to said longitudinal member at a point spaced rearwardly of the transverse member.
2. A kite as defined in claim 1 in which said connection for said string consists of a flexible yoke having its ends connected to said longitudinal member in spaced relation on opposite sides of the center of gravity of the kite,
and a string connection to said yoke located closer to the front of the yoke than the back.

3. A kite as defined in claim 2 in which said transverse member is substantially longer than said longitudinal member.
4. A kite as defined in claim 3 in which said transverse member is approximately twice as long as said longitudinal member,
and the string connection to said yoke hangs below a point between the center of gravity of the kite and the forward end of said longitudinal member.
5. A kite as defined in claim 1 in which said tail is removably secured in place by means of a hole formed in a lower portion of the tail receiving the rear end of the longitudinal member,
and a flexible band secured to the underside of the longitudinal member and passed downwardly through a notch in the lower edge of the tail and looped upwardly over the rear end of the longitudinal member.
6. A kite as defined in claim 1 in which the leading edges of said sail members are attached to said transverse member by strips of removable adhesive tape permitting adjustment of the slack in side edges of the sail members.
7. A kite as defined in claim 1 in which said side edges of said sail members have convexly curved ends joined by a concavely curved central portion.
8. A kite as defined in claim 2 in which said sail members are made of a single sheet of flexible material having a line of holes formed therethrough along the longitudinal axis thereof,
and a strip of adhesive material applied to said sheet along said line and adhered to said longitudinal member through said holes.
9. A kite as defined in claim 2 in which said sail members are lapped on the undersides of said longitudinal and transverse members,
and said tail projects above and below said longitudinal member with the major proportion of the area of the tail above the longitudinal member.
10. A kite as defined in claim 2 in which the weight of said tail is approximately one-twelfth the total weight of the kite.
